CLAIM

The ornamental design for a holder for toiletry items, as shown and described.

DESCRIPTION

FIG. 1 is a perspective view, as seen from the left, of a holder for toiletry items showing my new design;

FIG. 2 is a front elevational view thereof;

FIG. 3 is a right side elevational view thereof;

FIG. 4 is a plan view thereof;

FIG. 5 is a bottom view thereof; and

FIG. 6 is a rear elevational view thereof.

FIG. 1

FIG. 2

FIG. 3

FIG. 4

FIG. 5

FIG. 6
